REFRIGERATING DEVICE

Lawrence C. Smith, Kenmore, N. Y.

Application August 30, 1933, Serial No. 687,416

6 Claims. (Cl. 62—95)

This invention relates to refrigeration devices for use in the cooling or freezing of beverages or foods.

The invention will be found to reside generally in the formation of a cooling unit by an assembly of simple and inexpensive structures to provide a plurality of compartments or cells therein, proportioned to receive articles to be cooled. The invention, in one embodiment, is devised as a bottle chilling device with special provision therein as to thermal efficiency in the cooling of the bottles and the maintenance of uniform temperatures in the air surrounding the device. In another embodiment, the invention is directed to the formation of a domestic evaporator, wherein ice tray housings are formed by a similar structure with the addition of specially formed shelf and wall arrangement.

Other features of the invention are more specifically set forth in the accompanying specification and drawings, wherein:

Fig. 1 is a front elevation of a bottle cooling unit with the cabinet for receiving the same shown in section;

Fig. 2 is a section on the line 2—2 of Fig. 1;

Fig. 3 is a front elevation of a domestic refrigerator containing an evaporator constructed in accordance with the invention;

Fig. 4 is a side elevation of the evaporator of Fig. 3, with the cabinet shown in dotted lines.

In accordance with Figs. 1 and 2, the invention is incorporated in a device for cooling bottles or containers, and it comprises a fabricated cooling unit 10 of rectilinear shape, which is enclosed in a heat insulated cabinet 11. The cabinet is provided with a door 12 which provides access to a major portion of the unit.

Structurally, the unit 10 is formed of a plurality of spaced vertical partition members 13, formed with rows of regularly spaced apertured flanges 14 through which tubes 15 are pressed and soldered to provide a cell-like structure. The protruding ends 16 of each vertical row of tubes are connected by vertical U-fittings 17 to connect the tubes in each row in series, and the free ends of each row of tubes are connected by horizontal U-fittings 18 to provide a continuous passage through all the tubes.

The upper terminal 19 of the tubing system may be connected to a pipe 21 which protrudes through the cabinet for connection to a suitable supply conduit of a refrigeration system (not shown), while the lower terminal 22 may be connected to a similarly disposed pipe 23 for communication with the suction side of the refriger-

ation system. The refrigeration system may be of any type known in the art, and its supply function through the pipe 21 may be controlled by a thermostatic expansion valve or similar device, which, in turn, is made responsive to temperature conditions in the cabinet through the usual expansion bulb 25.

The spacing of the partition members 13 is such that, in cooperation with the tubes 15, square pockets or cells 26 are formed which are of suitable proportions to receive bottles 27, with slight clearance between the bottles and the adjacent walls of the cells. It is preferred that the cabinet be mounted to permit the bottles to be disposed horizontally, so that they will rest on the tubes 15 to provide direct thermal contact therewith. This arrangement permits the bottles to rest on the grid-like tube shelves through which the water of condensation may gravitationally escape to the bottom 28 of the cabinet 20 for disposal through a drain 29, provided therein.

The vertical partition members 13 cooperate to impart thermal efficiency to the unit by providing for uniformity of temperature therethrough. As the tubes 13 are vertically disposed and of a considerable effective surface area, they are engaged by the downwardly moving air streams to effect a thorough heat exchange action. With the cells filled with bottles, this general downward air movement is partially blocked, but not completely, as the cooled air may find general downward paths through the corner spaces in the cells and thus travel downward in a tortuous path.

As shown in Fig. 2, the rear wall 31 of the cabinet is utilized as a stop member for limiting the rearward positioning of the bottles in the cells 26. It will be noted that the vertical wall members 13 are spaced from the wall 31 to permit the air circulation previously described.

In Figs. 3 and 4 a second embodiment of the invention is shown, and it comprises a cooling unit 33 formed as a domestic evaporator, mounted in a refrigerator cabinet 34. The general structure of this unit will be found to be similar to the structure of the described embodiment, vertical partition members 35 being devised for the reception of horizontal rows of tubes 35, which are connected by vertical and horizontal U-fittings 37 and 38 to form a refrigerant circuit. The cells 39 thus formed are, in this case, devised to be isolated from each other and from the ambient air in the cabinet to obtain the low temperatures necessary in the forming of ice.

Cover members 41 are provided to enclose the top and rear walls of the cells 39, and they com-

prise sheet metal structures each having a shelf portion 42 terminating at one extremity in a reverse flange 43, and at the opposite extremity in a depending rear wall portion 44. These members are easily assembled with the unit by hooking the flange portions around the foremost tubes and then swinging the rear wall portions 44 over the rear tubes to bring the shelf portions into engagement with the horizontal tube rows. The assembled structure may then be soldered at desired points to provide a rigid assembly.

Each cell 39 is proportioned to receive a container or ice tray 46, the tray front 47 of which is preferably devised to engage the flanges 43 to provide a closure for the front of its cell. Otherwise the trays 46 may be of conventional design.

The evaporator thus formed will be found to form ice in short periods of time, due to the fact that each tray shelf is adequately refrigerated. The outside portions of the device, including the loops, perform the usual function of cooling the air in the cabinet, and their effective aggregate surface area may be varied according to requirements by lengthening the protruding portions of the partitions 35 to provide exterior fins.

It is intended that the two embodiments of the invention heretofore described be considered as exemplary of the invention, which may be modified or applied otherwise in the art within the scope of the following claims:

I claim:

1. A cooling device comprising a cabinet having a vertical wall formed with an enlarged opening, a closure therefor, a cooling unit mounted within said cabinet comprising a plurality of vertically disposed spaced partition members, said members being formed with a plurality of rows of aligned apertures, a plurality of tubes each extending horizontally through the partition members in the aligned apertures thereof and secured thereto to form therewith a plurality of horizontal cells, and means connecting the tubes to form a continuous refrigerant passage, said cells being each adapted to receive a container inserted therein through the opening in the cabinet, said cabinet having a rear wall spaced from said unit and forming a stop member for the containers inserted in the cells.

2. A cooling device comprising a plurality of vertically disposed spaced partition members, said members being each similarly formed with a plurality of rows of apertures, a plurality of tubes each extending horizontally through the partition members through the aligned apertures thereof and secured thereto to form therewith a plurality of horizontal cells, said cells being proportioned to receive containers therein in intimate thermal relation, and means connecting the tubes to form a continuous refrigerant passage.

3. A cooling device comprising a plurality of vertically disposed spaced partition members, said members being each similarly formed with a plurality of rows of spaced apertures, a plurality of tubes each extending horizontally through the partition members through the aligned apertures therein and secured thereto to form therewith a plurality of open horizontal cells, a shelf member on each horizontal row of tubes to isolate adjacent cells, a rear wall member closing the back of each cell, an ice tray slidably mounted in each cell and having a tray front closing the front of its cell, and means connecting the tubes to form a continuous refrigerant passage.

4. A cooling device comprising a plurality of vertically disposed spaced partition members, said members being each similarly formed with a plurality of rows of spaced apertures, a plurality of tubes each extending horizontally through the partition members through the aligned apertures therein and secured thereto to form therewith a plurality of open horizontal cells, means for covering the top and rear walls of each cell comprising an integral sheet metal member having a shelf portion covering the horizontal row of tubes in each cell, said shelf portion having an inturned flange at its front margin engaging around the foremost tube and a depending wall member at its rear margin extending downward to close the rear of the cell, and means connecting the tubes to form a continuous refrigerant passage.

5. A cooling device comprising a plurality of vertically disposed partition members, said members being each formed with a plurality of rows of spaced apertures, a plurality of tubes each extending horizontally through the aligned apertures of the partition members and secured thereto to form therewith a plurality of horizontal container receiving cells, and pipe loops exterior of the outer partition members for connecting the tubes to form a continuous refrigerant circuit, said loops cooperating to cool the air exterior of the device.

6. A cooling device comprising a plurality of vertically disposed partition members, said members being each formed with a plurality of rows of spaced apertures, a plurality of tubes each extending horizontally through the aligned apertures of the partition members and secured thereto to form therewith a plurality of horizontal container receiving cells, and means connecting the tubes to form a continuous refrigerant passage, said partition members projecting from the outermost cells to form fin members to cool the air exterior of the device.

LAWRENCE C. SMITH.
